UNITED STATES PATENT OFFICE.

WILLIAM B. PURVIS, OF PHILADELPHIA, PENNSYLVANIA.

PAPER-BAG MACHINE.

SPECIFICATION forming part of Letters Patent No. 430,684, dated June 24, 1890.

Application filed January 10, 1889. Serial No. 295,971. (No model.)

To all whom it may concern:

Be it known that I, WILLIAM B. PURVIS, a citizen of the United States, residing at Philadelphia, in the county of Philadelphia and State of Pennsylvania, have invented a new and useful Paper-Bag Machine, of which the following is a specification.

My invention relates to paper-bag machines, or, more specifically, to the mechanism for forming the bottoms of the paper bags, as is fully described and shown in the following specification and drawings.

My invention is intended to form the so-called "satchel-bottoms" upon paper bags formed with bellows side folds.

My invention consists of certain mechanism operating by suction to draw out the paper tube into the desired shape of the satchel-bottom, into which it is finally flattened and folded. It is not concerned with the machine by which the bellows side-fold tubes are formed. The tubes formed with bellows side folds are conducted upon endless aprons or carriers between formers, from which the air is exhausted or sucked by suitable means, thereby drawing the ends of the tube out against the sides of the formers, which are provided with irregularly-formed faces to impart the desired folds to the ends of the bag, which are finally flattened down and pasted to form the sealed satchel-bottom.

Referring for greater particularity to the drawings, Figure 1 is a side elevation of a portion of a paper-bag machine embodying the principles of my invention. Fig. 2 is a plan view of the same. Fig. 3 is a cross-sectional view on line $x-x$ of Fig. 2. Fig. 4 is a longitudinal sectional view of the formers through the line $y-y$ of Fig. 3. Fig. 5 is a perspective view, on an enlarged scale, of the formers separated to show the passage of the paper tubes through them and the formation of the satchel-bottom; and Figs. 6 and 7 are views of the completed bag.

A A are endless aprons or carriers running in contact with each other over rollers B, supported in a suitable manner upon the main frame C. I prefer to journal the shafts of these rollers in uprights upon the frame.

D D are the formers constructed with corresponding parts and supported upon the main frame on one side of the endless aprons

with a small space between them to receive the end of the tube which is to be formed into the satchel-bottom. These formers are box-shaped, and have a vertical portion d and a horizontal portion d' , the former of which is longer than the latter portion and thicker at one end than at the other, having a curved surface at the thicker end gradually diminishing. The inner surfaces of these formers are provided with a large number of holes or perforations through which the air may be sucked by the pipes E, connecting with any suitable vacuum-creating device F. These formers D are made with compartments G G G, closed from each other by the partitions g, and into each of these compartments separate pipes E lead provided with valves e, so that the suction may be varied at different portions of the surface of the formers D D. H is the pasting-roller, I the folder, and J J the flattening-rollers. The paper tubes with the bellows side folds are carried between the endless aprons A A, between the formers D D, and the suction therein created through the tubes E draws up the ends of the bag K against the faces of the former, as shown in Fig. 5. As the tubes continue to move, the ends are drawn farther apart, and upon reaching the second position (shown in Fig. 5) they are bent and drawn into the box shape by the suction upon the faces d and d' , respectively, of the formers D D and the groove formed between those faces. From this square box shape the ends are readily drawn into the folds shown in the third and fourth positions in Fig. 5 by the suction of the former. The bag then passes under the pasting-roller H, the folder I, and the flattening-rollers J J, from which it emerges in the form shown in Fig. 7.

The important feature in this operation is the drawing out of the bellows side folds and forming the square box shape, which is accomplished by the groove between the portions d and d' of the formers; and I find it very advantageous to make that groove at about the center of its length with this slit or opening M, Fig. 5, through which the air is sucked or drawn. This groove forms the necessary crease to break the ends of the tube into the square box shape to form the satchel-bottom, and by making the groove with this

slit or opening as described the operation is more effectively performed. If desired, the portions *d* and *d'* may be made separate, forming an opening in the groove between them, and the parts may be made adjustable to increase or diminish the width of the opening in the groove. Small wires *k* may be stretched (preferably in a slanting or oblique direction) across the upper and front portion of the formers to aid in forming the square box shape; but this is of course not essential to my invention, nor is the exact shape of the formers important if the general shape is such as described as necessary to make the required folds in the end of the paper tube. A hood or enveloping cover *L* may be secured over the rear ends of these formers *D D* to form a compartment between the two formers, and thus aid the flow of the air.

The mere details of construction which are here shown are manifestly capable of modification without departing from the principles of my invention, and are therefore not to be considered limitations of it.

Having now described my invention, what I claim as new, and desire to secure by Letters Patent, is—

1. In a machine for forming bottoms of paper bags, two box-shaped formers between which the paper tubes to be formed are fed, having perforated surfaces and grooves extending longitudinally therein, in combination with means, substantially as described, to suck the air through said perforations and draw the ends of the paper tubes against the faces of the formers.

2. In a machine for forming bottoms of paper bags, two box-shaped formers between which the paper tubes to be formed are fed, having perforated surfaces and grooves extending longitudinally therein, in combination with means, substantially as described, to suck the air through said perforations and draw the ends of the paper tubes against the faces of the formers; and a carrier to carry the paper tubes between the formers.

3. In a machine for forming a satchel-bottom on a bellows side-fold tube, the combination of two hollow formers between which the end of the paper tube is fed, said formers having curved faces provided with holes or perforations, through which the air is sucked to draw the ends of the paper tube up against the faces of the formers, and a groove in each of said faces, into which the end of the tube is drawn to form the satchel-bottom, said groove having a slit or opening in the direction of its length into the interior of the formers.

4. In a machine for forming a satchel-bottom on a bellows side-fold tube, the combination of two hollow formers, between which the end of the paper tube is fed, said formers having curved faces provided with holes or perforations, through which the air is sucked to draw the ends of the paper tube up against the faces of the formers, a groove in each of said faces, into which the ends of the tube are drawn to form the satchel-bottom, and pasting devices to apply paste to the ends of the folded tube, and a folder to fold said pasted ends over upon each other.

5. A former for forming the bottoms of paper bags by suction, consisting of two similar box-shaped portions arranged opposite to each other, each having a curved face provided with perforations or holes and a longitudinally-extending groove therein, said box-shaped portions being divided into compartments closed to each other, in combination with means, substantially as described, to exhaust the air from any or all of said compartments.

6. A former for forming a satchel-bottom on a paper bag, consisting of two similar and oppositely-arranged box-shaped formers, each having the vertical portion *d*, with a curved and gradually-receding surface, and the horizontal portion *d'*, said portions *d* and *d'* having a longitudinal groove or depression between them and being provided with perforated surface, through which the air is sucked to draw the edge of the paper tube against said surfaces of the former.

7. In a machine for forming bottoms of paper bags, two box-shaped formers, between which the paper tube to be formed is fed, having perforated surfaces and grooves extending longitudinally therein, in combination with means to create a suction through said perforated surfaces, and a hood or cover extending partly over said formers.

8. In a machine for forming bottoms of paper bags, two box-shaped formers, between which the paper tube to be formed is fed, having perforated surfaces and grooves extending longitudinally therein, in combination with means to create a suction through said perforated surfaces, and wires arranged transversely upon said faces of the formers to present a roughened surface, over which the paper tube is to pass to aid the formation of the bottom.

In testimony of which invention I hereunto set my hand.

WILLIAM B. PURVIS.
